COLLAR

Filed Jan. 21, 1928

Inventor

PETER TURPAN
By His Attorney
Irving L. McCathran

UNITED STATES PATENT OFFICE

PETER TURPAN, OF PATERSON, NEW JERSEY

COLLAR

Application filed January 21, 1928. Serial No. 248,402.

This invention relates to collars and in particular to those arranged to be worn in connection with a collar band of an outer shirt.

5 A particular object of the invention is to provide a collar, the outer portion of which will be prevented from wrinkling when the tie has been tied and is in position therein.

10 A still further object of the invention is to so cut a collar that when the same is folded and bent into wearing position, the material of the outer portion thereof will be taken up so that the collar at its front ends or points is taut and is maintained rigidly in 15 position so that distortion thereof cannot readily take place.

15 A still further object of the invention is to provide a collar made in a single piece, the same being cut on an arc so that when the same is folded, the material of the collar band will take up and will cause the outer portion of the collar to retain its shape.

20 To enable others skilled in the art to fully comprehend the underlying features of my invention that they may embody the same in the various modifications in structure and relation contemplated, drawings depicting a preferred form have been annexed as a part of this disclosure and in such drawings, similar reference characters denote corresponding parts throughout all the views, of which,

25 Figure 1 is a view in front perspective of a collar constructed in accordance with my invention the same being shown in outline 30 as it would appear when opened out, and

35 Figure 2 is a plan view of the collar opened out, the same being arranged to illustrate how the single piece collar is cut on an arc to prevent wrinkling of the outer portion thereof.

40 Referring to the drawings in detail and in particular to the form shown in Figures 1 and 2, 5 indicates the outer portion and 6 the collar band portion of a collar constructed in accordance with my invention, the collar band 6 being provided at its ends with the buttonhole tabs 7 and buttonholes 8 through 45 the medium of which the collar may be secured in position on the neckband of a shirt.

50 As is usual in the soft type of collar made of linen or other suitable fabric, the outer

portion is provided with the pointed extensions 9 and heretofore difficulty has been encountered in preventing these extending points and the sides of the collar adjacent thereto from wrinkling and with a view to 55 eliminating this fault, I have conceived the idea of cutting a single piece of material to form the neckband 6 and outer portion of the collar 5 arcuately so that the lower edge 12, the line of sewing 11 and the lower edge 10 60 of the outer portion 5, will be cut on arcs, the radii of which have a common center.

It has been found that when a collar so constructed is bent into shape for wear and is placed about the shirt neck band, that the outer portion thereof 10, will be drawn up 65 to prevent the same from wrinkling or sagging due to the drawing in of the collar band when the tie is knotted or otherwise tied.

In order to shape the collar, the same is 70 provided with the line of sewing 11 which, as before stated, is substantially parallel to the lower edges of the collar band 6 and outer portion 10.

If desired, this collar may be made of a 75 single ply of material or of two plies sewn together in any suitable manner. In any event, the entire collar may be made from the single piece of material without pleating or otherwise sewing of the parts together. 80

It is evident, therefore, that I have provided a new and improved type of collar which can be made of a single piece and which will prevent the outer portion thereof from 85 wrinkling or becoming distorted during wear.

It is also evident that I have provided a collar, the goods of which can be cut out in a single operation, thereby eliminating the necessity of sewing and consequently, providing a collar which can be produced at lower 90 cost than has heretofore been possible.

While I have illustrated and described my invention with some degree of particularity, I realize that in practice various alterations 95 therein may be made. I therefore reserve the right and privilege of changing the form of the details of construction or otherwise altering the arrangement of the correlated parts without departing from the spirit of 100

the invention or the scope of the appended claim.

Having thus described my invention what I claim as new and desire to secure by United States Letters Patent is:—

- 5 The method of manufacturing a collar which consists in cutting the opposite, longitudinal edges of a single piece of material arcuately on radii having a common center to form a collar band, and an outer portion, and providing an arcuate line of stitching, the center of the radius of which is at said common center, between the collar band and the outer portion, to shape the collar, and the radius of the arcuate edge of said outer portion being shortest.
- 10
- 15

In testimony whereof I affix my signature.

PETER TURPAN. [L. s.]
